UNITED STATES PATENT OFFICE

JOSEPH A. LOGAN AND WARREN H. DE LANCEY, OF SPRINGFIELD, MASSACHUSETTS,
ASSIGNORS TO GILBERT & BARKER MANUFACTURING COMPANY, OF WEST SPRING-
FIELD, MASSACHUSETTS, A CORPORATION OF MASSACHUSETTS

LIQUID DISPENSING APPARATUS

Application filed November 15, 1929. Serial No. 407,532.

This invention relates to improvements in liquid dispensing apparatus, of a type adapted for dispensing gasoline, oils and the like.

The invention has for one object the provision of improved means for locking up the nozzle of the dispensing hose, when not in use, preferably in a manner such that it not only cannot be used but also so that it is protected from the weather.

10 The invention also has for an object the provision of hose nozzle locking means of a type which will also prevent opening of the valve of the nozzle while the latter is locked up.

15 Another object of the invention relates to a liquid dispensing apparatus, having a power-operated pumping means with means for starting and stopping the same, and consists in an arrangement, whereby the hose 20 nozzle when in position for locking prevents operation of said starting and stopping means.

A further object of the invention relates to a liquid dispensing apparatus having a plurality of delivery hoses, all served from a single power-operated pumping means, and consists in an arrangement, whereby the flow to any one hose must be stopped before the nozzle of that hose can be placed in position 30 for locking and whereby the pumping means must be stopped before all the hose nozzles can be placed in position for locking.

I have chosen as an illustrative embodiment of my invention, a so-called meter-type dispenser, including an electrically or other power driven pump which supplies two discharge lines, each including a meter. The invention, however, is capable of use in many other dispensers, which differ widely from 40 that herein shown, and it is therefore not the intention to have the invention restricted to the particular form of dispenser shown.

Other objects and advantages will appear in the following description and will be 45 pointed out in the appended claims.

The invention will be disclosed with reference to the accompanying drawings, in which:—

50 Figs. 1 and 2 are front and side elevational views, respectively, of a dispensing appara-

tus embodying our invention,—the enclosing casing of the apparatus being shown in section and certain parts being broken away to reveal interior mechanism;

Fig. 3 is a sectional plan view taken on the line 3—3 of Fig. 1;

Figs. 4 and 5 are fragmentary views, taken from the same direction as Fig. 2 but drawn to a larger scale to clearly show the detail of the valve and switch operating mechanism; and

Fig. 6 is a sectional view taken on the line 6—6 of Fig. 5.

The apparatus includes a framework (Figs. 1 and 2) made up of a base 10, a cap 11 and four upstanding pipe columns 12, which are secured at their lower ends to the base and at their upper ends to the cap. The space between the base and cap is enclosed by a two-part sheet-metal casing 13 of modified square cross section. The cap 11 is formed with lateral openings 14 (Fig. 2) in the front and back, through which electric lamps 15 may extend. The cap is also provided with outwardly projecting parts 16 which form hoods for the lamps. The cap may also support the usual ornamental illuminated globe, indicated in part at 17. The several lamps are mounted in sockets, such as 18, and these in turn are supported by conduits 19, carrying the supply wires 20.

In the lower portion of the apparatus is a suitable pump 21, having a rotary drive shaft 22, suitably coupled, as by a flexible coupling 23 to the drive shaft 24 of an electric motor 25. The motor and pump are suitably secured to the upper and lower ends, respectively, of a frame 26. This frame lies between and is bolted to a pair of angle irons 27. Each angle iron is secured to the adjacent pipe column 12 by U-bolts 28. A conduit 29 leads, from a position near the base 10, upwardly to a condulet 30 which is suitably secured to the frame or motor 25 and carries a branch conduit 31 leading to a switch housing 32. The switch, contained in housing 32, has a lever 33 which normally occupies the position shown in Fig. 2 and tends to assume that position wherein the switch is open. This switch controls motor 100

25, being suitably connected in circuit therewith by wires contained in conduits 29, 30 and 31.

The suction side of pump 21 is connected 5 to a pipe 33', adapted for connection to an underground supply tank. To the discharge side of the pump, a pipe 34 is connected which supplies two branch pipes 35, each leading to a suitable flow meter 36. Connected to pipe 34 is an air dome 37. Interposed in each branch pipe 35 is a suitable stop valve 38, having an operating shaft 39, carrying a lever 40. The flow meters 36 have dials 41 and indicators 42 (Fig. 1) which are 10 visible through suitable openings 41' in casting 13, as will be clear from Fig. 2. The discharge pipe 43 for each meter leads horizontally outward, thence upward to cap 11 and thence outward through a suitable opening in the cap. To the end of pipe 43 is attached a suitable sight glass 44 and to the latter the usual dispensing hose, shown in part at 45. The free end of each hose carries 15 a valved hose nozzle 46, having an operating lever 47 and a guard 48 for the latter.

The two meters are supported by and between a pair of plates 49. The inner and adjacent corners of these plates are cut off at an angle, as at 50 (Fig. 3). This allows 20 the body of meter 36 to enter between the pair of plates far enough so that two of the studs 51, which secure the sections of the meter housing, can be passed through holes in the plates and secured thereto by nuts 52. 25 The outer and non-adjacent edges of plates 49 have upstanding flanges 53, each of which abuts a pipe column 12 and is clamped thereto by a U-bolt 54.

Intermediate the two flanges 53 of each 30 plate is a centrally located and forwardly extending part 55, which terminates with a downwardly turned flange 56. Secured to each such flange is a bracket 57, which extends outwardly through casing 13 and, near 35 its outer end, carries an upwardly extending lug 58 having a hole 59 therethrough. The hose nozzles 46 are adapted to be supported one on each bracket 57. Part of the guard 48 of each hose nozzle can rest on bracket 57 40 as shown in Fig. 1 while the remainder of the guard abuts casing 13. The lug 58 passes through a slot in the guard 48 and prevents movement of lever 47 to an extent sufficient to open the valve of nozzle 46, as will be clear 45 from Figs. 1 and 3. Hole 59 is provided to receive a padlock, by which nozzle 46 can be locked in place in inactive position. Before the nozzle can be supported as described, its upper end must be inserted in a hole 60 in 50 casing 13.

Levers 61, one for each meter of the apparatus, are provided for operating, from a point outside the casing, the motor switch and the two valves 38. Each such lever is 55 fixed to the outer end of a shaft 62. The two

shafts are mounted in axial alignment (Fig. 3) and their inner ends are connected by a sleeve 63 but in such a way that each shaft can be turned independently of the other. The aligned shafts 62 are rotatably supported by two bearing bushings 64, secured one in each flange 56 and below the bracket 57. Each bushing passes through flange 56 and has a flange 65 (Fig. 6) to abut the outer face thereof. The inner end of each bushing is 70 threaded to receive a nut 66 by which the bushing is clamped to flange 56. Each shaft is held against undue endwise movement between the hub of its lever 61 and a collar 67 75 fixed to the shaft.

Each shaft 62 has fixed thereto a lever 68 and both these levers are located inside housing 13. Each lever 68 carries two heads 69 and 70, arranged one on each side of the lever and at radially spaced points. Each of these heads is mounted to turn freely in the lever about an axis parallel to that about which the lever turns. A link 71, in the form of a round rod, is threaded at one end into each head 69, or otherwise adjustably connected thereto, and at its other end is slidably engaged with a head 72, having a vertical trunnion 73 which loosely fits in a hole in a valve lever 40, being held in place by a pin 74. An abutment 75 is formed on each link 71 to engage one face of its head 72 and the opposite face thereof is engaged by a spring 76 coiled around the link and held in place by a washer 77 and cotter pin 78. The other head 70 in each lever 68 is connected by a link 79 to the switch operating lever 33. Link 79 is threaded in head 70, or otherwise adjustably connected thereto, and near its other end has shoulders 80. The connection of both links 79 to lever 33 is effected by means of substantially U-shaped pieces 81, arranged one on each side of lever 33 with the cross bar portion of each engaging the lever and pivotally connected thereto by a pin 82. The links 79 are slidably engaged, one in each of the members 81, sliding in the outstanding ears thereof, until arrested by the engagement of the shoulders 80 with the uppermost ears.

With the parts positioned as in Fig. 4, both valves 38 are closed and the motor switch is open. With both hose nozzles hung up on their respective supports, the guards 58 of the hose nozzles will prevent movement of levers 61 in such directions as would cause opening of their respective valves or closing of the motor switch. Movement of either lever 61 in the opposite direction is permitted to a limited extent by the springs 76 but not to any such degree as would enable the links 79 to be drawn out of the ears of members 81. With either hose nozzle removed from its support, one of the levers 61 is then free to move into a position such as shown in Fig. 5, and when so moved causes the opening of the 11

valve 38, controlling the pipe which supplies the nozzle thus removed. Also the switch lever 33 is moved to "on" position. In opening the valve 38, the shoulders 75 engage head 5 72 and thus move lever 40. In closing this valve the transmission from link 71 to head 72 is through spring 76 and, after the valve has been closed, this spring yields, if necessary, to allow lever 61 to be brought back far 10 enough to permit the hose nozzle to be hung up on its support. It is usually desirable to have the movement of link 71 somewhat in excess of that required to close the valve to insure a tight closure of the same,—the spring 15 76 taking care of any overtravel of the link. In closing the motor switch the shoulders 80 on the particular link 79, which is moved downwardly, engages its member 81 and moves the same. When this link is drawn 20 upwardly by the movement of lever 61 into valve closing position, the link 79 will slide in member 81, but the switch lever will be restored to the position shown in Fig. 4, by the mechanism of the switch which is of the 25 self opening type. To hold the switch closed, the pivot 70 between lever 68 and link 79 is arranged to cross slightly to the left (as viewed in Fig. 5) of the line connecting the centers of shaft 62 and pivot 82. The valve lever 40 30 can move only through a limited arc and, when the valve is opened as shown in connection with the left valve in Fig. 5, its lever 40 limits the extent to which the pivot 70 can cross the aforesaid line of centers.

35 In operation, one or the other of the hose nozzles must be removed before the operator can start the pump motor or open either of the valves 38. Having removed a hose nozzle, the operator moves lever 61 into a 40 position, such as shown in Fig. 5, and far enough so that the lever will remain in its moved position due to the "crossing centers" action, above described. By so doing, the pump 21 is set in operation and that valve 38, 45 which controls the flow to the nozzle thus removed from its support, is opened. The operator then inserts the nozzle in the filling opening of a gas tank and controls the flow by means of the lever 47 of the nozzle valve.

50 When the liquid delivery operation has been completed the operator naturally wishes to hang up the nozzle and the only means provided for this purpose is the bracket 57. Before the operator can hang up the nozzle on 55 this bracket, he must move lever 61 out of interfering relation with the bracket and by so doing, he causes the valve 38 to close and, if the other nozzle is also hung up, stops the pump motor. The stopping of the motor, 60 however, cannot take place until both nozzles are hung up. That is, while each valve is independently controlled by a lever 61, the control of the motor by the levers, insofar as stopping it is concerned, is a joint action.

65 Either lever can be moved to start the motor

but both must be moved to locking position before the motor can be stopped. The locking of the hose nozzle on its support also locks the hose nozzle valve lever 47 and the lever 61. The invention has been disclosed herein, in 70 an embodiment at present preferred, for illustrative purposes, but the scope of the invention is defined by the appended claims rather than by the foregoing description.

What we claim is:

1. Liquid dispensing apparatus, comprising, a motor operated pump, a switch for stopping and starting the motor, two discharge pipes from said pump, a meter interposed in each pipe, a casing enclosing the aforesaid elements except for openings through which the indications of said meters may be seen, a delivery hose connected to the delivery end of each discharge pipe and extending outside the housing, a nozzle on the delivery end of each hose, supports outside the casing, one for each nozzle, a lever adjacent each support, each lever mounted to swing from an inactive position to an active position in a path closely adjacent the outer end of its support, each nozzle interengaging with its support so that a part of the nozzle extends into the path of the adjacent lever and holds it in its inactive position, a shaft for each lever extending into said housing, an arm on each shaft, a lever on said switch tending to move to "off" position, a pair of heads one on each side of the switch lever and swivelled thereto, and a link connection between each arm and head, each link having a shoulder to engage its head and move the switch lever to "on" position and freely slideable in its head in the general direction in which the switch lever moves to reach "off" position, either lever when moved from inactive to active position effective to move the switch lever to "on" position unless it has previously been so moved by the other lever, and movement of both levers into inactive position being necessary before said switch lever can move to "off" position.

2. Liquid dispensing apparatus, comprising, a motor operated pump, a switch for stopping and starting the motor, two discharge pipes from said pump, a meter interposed in each pipe, a casing enclosing the aforesaid elements except for openings through which the indications of said meters may be seen, a delivery hose connected to the delivery end of each discharge pipe and extending outside the housing, a nozzle on the delivery end of each hose, supports outside the casing, one for each nozzle, a lever adjacent each support, each lever mounted to swing from an inactive position to an active position in a path closely adjacent the outer end of its support, each nozzle interengaging with its support so that a part of the nozzle extends into the path of the adjacent lever and holds it in its inactive position, a shaft

for each lever extending into said housing, an arm on each shaft, a lever on said switch tending to move to "off" position, a pair of heads one on each side of the switch lever and swivelled thereto, and a link connection 5 between each arm and head, each link having a shoulder to engage its head and move the switch lever to "on" position and freely slideable in its head in the general direction in 10 which the switch lever moves to reach "off" position, either lever when moved from inactive to active position effective to move the switch lever to "on" position unless it has previously been so moved by the other lever, 15 and movement of both levers into inactive position being necessary before said switch lever can move to "off" position, the pivotal connection between each link and its arm crossing the line of centers, connecting the center of its shaft and the center of its switch lever head, whereby the switch lever is held 20 in "on" position.

3. In a liquid dispensing apparatus, a base, a cap, two pairs of columns connecting the 25 base and cap, a casing enclosing the space between the base and cap and having an opening, a meter including a dial to aline with said opening, and a pair of sheet metal plates one for each pair of columns, each plate extending 30 between the columns of its pair and having near one edge right angularly bent ears to engage such columns, means for clamping said ears to the columns in a manner enabling vertical adjustment of the plate, 35 said plates extending horizontally toward each other and between them supporting the meter.

4. In a liquid dispensing apparatus, a base, a cap, two pairs of columns connecting the 40 base and cap, a casing enclosing the space between the base and cap and having an opening, a meter including a dial to aline with said opening, and a pair of sheet metal plates one for each pair of columns, each plate extending 45 between the columns of its pair and having near one edge right angularly bent ears to engage such columns, means for clamping said ears to the columns in a manner enabling vertical adjustment of the plate, said plates 50 extending horizontally toward each other and between them supporting the meter, power operated pumping mechanism in said casing below said plates for forcing liquid to and through the meter, said plates each having a 55 part extending toward one wall of the casing and terminating closely adjacent thereto with a vertically disposed ear, a shaft supported by said ears and having an end extending outside said casing, a lever fixed to said 60 end, and means operated from said shaft for controlling said mechanism.

In testimony whereof we have affixed our signatures.

JOSEPH A. LOGAN.
WARREN H. DE LANCEY.
